UNITED STATES PATENT OFFICE.

WALTER DEXTER, OF BROOKLYN, ASSIGNOR TO A. G. JENNINGS, OF NEW YORK, N. Y.

DESIGN FOR NETTED FABRICS.

Specification forming part of Design No. 5,981, dated July 16, 1872.

Specification describing a new and original Design for Netted Fabrics, invented by WALTER DEXTER, of Brooklyn, in the county of Kings and State of New York.

The nature of my design is fully represented in the accompanying drawing, to which reference is made.

The drawing represents a face view of my new design.

This invention consists in forming the pillars *a a* of a series of thread loops or meshes, connected together so as to give them the gen-

eral appearance of plain-link chains. The same are shown in connection with heavy pillars *b b*, of peculiar outline; but I do not restrict myself to the design thus formed.

What I claim is—

The design for pillars for net fabrics, as shown.

WALTER DEXTER.
